CLAIM

The ornamental design for a combined carrying case and folding seat, substantially as shown and described.

DESCRIPTION

FIG. 1 is a top plan view of a combined carrying case and folding seat showing our new design;

FIG. 2 is a bottom plan view thereof;

FIG. 3 is a left side elevational view thereof;

FIG. 4 is a front elevational view thereof;

FIG. 5 is a rear elevational view thereof;

FIG. 6 is a perspective view of the combined carrying case and folding seat in an open position; and

FIG. 7 is a rear perspective view thereof.

FIG. 1**FIG. 2****FIG. 3****FIG. 4****FIG. 5**

FIG. 6

FIG. 7
